UNITED STATES PATENT OFFICE.

ALFRED J. GILLESPIE, OF ATLANTIC, IOWA, ASSIGNOR TO U. S. STANDARD VOTING MACHINE COMPANY, OF ROCHESTER, NEW YORK, A CORPORATION OF NEW YORK.

VOTING-MACHINE.

No. 849,123.

Specification of Letters Patent.

Patented April 2, 1907.

Application filed August 30, 1904. Serial No. 222,697.

To all whom it may concern:

Be it known that I, ALFRED J. GILLESPIE, of the city of Atlantic, in the county of Cass and State of Iowa, have invented certain new and useful Improvements in Voting - Machines; and I do hereby declare the following to be a full, clear, and exact description of the same, reference being had to the accompanying drawings, forming a part of this specification; and to the reference-numerals marked thereon.

My present invention relates to that class of voting-machines employing straight-ticket mechanism, or devices whereby all the indicators devoted to different candidates nominated by the same political party may be moved to voted position at a single operation, and has for its object to provide means whereby machines adapted for a large number of candidates may be used when comparatively few candidates are nominated without the necessity of operating the straight-ticket mechanism, which is adapted only for the larger number of candidates; and to this end it consists in certain improvements hereinafter more specifically described, the novel features being pointed out in the claims at the end of the specification.

The invention is shown as applied to a machine of the class contained in my prior patent, No. 647,657, the principal variation, excepting for the invention hereinafter described, being that instead of arranging the ballot-indicators devoted to candidates of the same political party in vertical lines said indicators are arranged in horizontal lines and are moved vertically instead of horizontally into voted position, the devices for operating the indicators of all the candidates for the different political parties being located at the end of the horizontal row of indicators.

In the accompanying drawings, Figure 1 is a front view of a portion of the keyboard of a voting-machine provided with my improvements, one of the straight-ticket handles or indicators being shown in an abnormal position in full lines and in dotted lines in a position which it occupies when indicating a vote for all the candidates devoted to that particular party. Fig. 2 is a rear view of the parts shown in Fig. 1. Fig. 3 is a rear view of a sectional straight-ticket bar with one of

the sections disconnected. Fig. 4 is a perspective view of the rear portion of a voting-machine provided with my improvements, showing means as for retaining and insuring proper operation of the straight-ticket bars. Fig. 5 is a view of an operating-tool employed for disconnecting the sections of the straight-ticket bar. Fig. 6 is a perspective view of the rear of the machine, showing the manner of disconnecting the bars. Fig. 7 is a sectional view on the line *xx* of Fig. 4.

Similar reference-numerals in the several figures indicate similar parts.

The ballot indicators or keys shown in the drawings are substantially the same as those contained in my prior patent, being mounted to turn in bearings in the front plate 1 of the machine and having at the front of said plate the operating handles or portions 2 and at the rear the arms 3, carrying the segmental plates 4, adapted to cooperate with the hooked ends of the actuators 5 of the counters, and also connected with the interlocking rods, which latter, however, are not shown herein. These keys or indicators are also provided with lugs or projections 6, with which the straight-ticket bars are adapted to coöperate to cause the movement to voted position of the line of keys devoted to candidates nominated by the same party. The forward portion 2 of the key is adapted to project over the label or ticket bearing the candidate's name and arranged in the label-holders 7 beneath them.

The straight-ticket bars in my present machine, instead of being made of a single piece of material, as heretofore, are each composed of a number of sections, three being shown in the present instance, capable of connection so that the bars may be moved as a unit when all of the indicators of a horizontal line are in use, said sections being, however, capable of disconnection, so that one or more may be employed if a smaller number of offices are to be provided for and without the necessity, therefore, of operating all of the indicators in the party-line. This capacity of the machine is particularly useful in connection with that class of machines now extensively in use and described in my prior patent, No. 628,905, which require that a straight-ticket mechanism be operated be-

fore the machine is interlocked to permit the separate actuation of the individual-candidate indicators.

In the present embodiment of my invention I have shown the straight-ticket bars as composed of three sections, (indicated by 8 8^a 8^b,) the adjacent ends of the sections being provided with hooks or detachable connections, which insure the positive movement of all the sections in a direction to actuate the indicators to permit the disconnection of one or more of the sections when not in use.

As is shown in Figs. 2 and 3, the forward end of the second and all subsequent sections of the straight-ticket bar is provided with a hook 9, and the rear end of the adjacent section ahead of it is provided with a corresponding hook 10, which hooks 9 and 10 are so related as to engage each other and hold connected the sections of which they are a part. Each of these sections 8^a and 8^b are recessed at 11 to permit the bar to rise without interfering with or being interfered with by the pivots 12 of the links 13. It is apparent that the straight-ticket key 14 is connected to the first bar by means of a crank 15, and the other end of this first section of the bar is supported by a link 13, before referred to.

The second section 8^a of the straight-ticket bar is supported at its forward end by the rear end of the preceding bar and its rear end by the link 13, and each succeeding bar is supported in like manner. I preferably arrange these bars in length so that a single section will engage with ten keys, and the last section is divided into two parts, so that each of its portions will engage with five keys. Thus five, ten, twenty, or thirty keys may be thrown out of action in a machine that is forty keys long, which of course makes the straight-ticket key move correspondingly more easily and enables me also to use the keys which are thus rendered idle for voting for candidates which must be nominated by petition independent of parties, it being frequently the case that such candidates must be voted for in the same election where full party tickets are put in nomination for other offices the candidates for which are nominated by party convention in the ordinary way. It is also possible to leave, for example, five of the straight-ticket bars connected up through their full length, disconnecting a portion of the sections of the sixth and seventh straight tickets in a machine having seven rows, for instance.

It sometimes happens that four or five parties will nominate full tickets, which will occupy approximately the whole length of the keyboard, and the sixth and seventh parties in a seven-row machine will only nominate a State ticket, which of course would come at the head of the keyboard and

may be composed of but eight or ten candidates. If there is then an extra party or two in the field nominating candidates by petition for some of the minor local offices, I can place these candidates on the sixth or seventh party-rows in the lines of the offices for which they are running, thus enabling me to provide for eight or nine parties, such as are frequently found in an election on a seven-party machine.

The sections of the straight-ticket bar are connected or disconnected in the following manner: The crank 11 of the straight-ticket key carries the pin 14, which projects through the first section of the straight-ticket bar, and the section of the straight-ticket bar may be secured on this pin by means of a cotter-pin or any other suitable device. The straight-ticket keys or actuators 15 are normally held in the position indicated by the top and bottom straight-ticket keys in Fig. 1, and they are held in this position by a bar 16, (shown in Fig. 4,) which passes immediately behind the cranks of the straight-ticket keys on the rear of the keyboard. As long as this bar is in position the straight-ticket keys are prevented from assuming the position of the middle key. (Shown in Figs. 1 and 2.) This bar, however, is made removable, and when removed the straight-ticket keys can then assume the position indicated by the middle key in Figs. 1 and 2. When the bar is so removed and it is desired to disconnect one or more of the sections of any of the straight-ticket bars, the straight ticket is first pulled to voted position, throwing the small keys down to voted position on the front of the keyboard and raising the parts corresponding to them on the back of the keyboard. The straight-ticket key is then turned to the position in which the middle key is shown in full lines in Fig. 1, thus taking the end of the last section from under the pivot 12 of the link 13, after which the hooked end of the section that is to be disconnected is raised and the section and all to the left of it pushed back and held in this position by a pawl 17 or other suitable securing device engaging the last section. I have shown only the last section 8^b disconnected; but it will be understood that both sections 8^a and 8^b could be disconnected in a similar manner from section 8, the pivot-holding section 8^b, while section 8^a would be moved and held with it.

If it is desired to disconnect the sections of any other straight-ticket keys, it is first necessary to reset the small or candidate keys to release the interlocking mechanism, as will be understood, so that any other straight-ticket-key may be placed in voted position the sections of the bar of which it is desired to disconnect. When all of the disconnections are made that are desired, the straight-ticket keys may be held in their normal position and the bar 13 returned to its proper

place, which will prevent the straight-ticket keys reaching or assuming the position shown by the middle key in Fig. 1. As long as the straight-ticket keys are held from assuming this position the hook 9 of each of the detachable sections must come under the pivot 12 of the link 13, which prevents it from raising to disengage itself from the forward section—that is, it cannot lift up sufficiently to disengage itself. The link 13 also laps over both the adjacent ends of the forward and rear sections, preventing them from disengaging laterally. It will thus be seen that I have provided a ready and effective way for connecting or disconnecting the various sections of a straight-ticket bar which can be applied to a machine of any length. It is understood that these straight-ticket bars are ordinarily concealed by the counter-channels 20, such as are described in my previous applications; but there is a small space between each of those channels, through which a thin piece of steel can be inserted to raise the section that it is desired to disconnect, thus making it accessible without taking the machine apart. A tool suitable for this is shown in Fig. 5, (indicated by 21,) the manner of using it being also indicated in Fig. 6.

30 The sections are connected by placing all the keys on the party-row in voted position, then by placing the straight-ticket key in the position indicated by the middle key in full lines in Fig. 1. Then the section that is to be connected is disconnected from the pawl 17, and the hooked end raised by the tool 21, the section moved to the right again, the outer end being free from the counter-channels, as in Fig. 6, when the hooked ends will become 40 engaged as before. As soon as the straight-ticket key is turned to normal position and the bars locked, as before, by the bar 16 the accidental disengagement of the sections will be prevented.

45 The bar 16 may be locked in position by any desired form of securing device; but I prefer to provide it with several keyhole-slots 22, through which project headed pins 23, the construction being such that the bar 50 can only be removed when raised to bring the heads of the pins in line with the larger apertures. To prevent this upward movement of the bar, the latter is provided with a spring-arm 24, having an aperture fitting over an 55 elongated pin 25, where the bar is in locked position, as shown in Fig. 7.

For the purpose of insuring the return of all the straight-ticket bars to normal position I 60 preferably bevel the ends of the sections 8, as shown at 30, and provide a vertically-movable bar 31 in the casing, having rollers or 65 projections 32 thereon engaging said beveled ends. This bar may be sufficiently heavy to return to lowermost position by its own weight; but I prefer to insure this by em-

ploying a spring 33, connected to the stationary pin 25, as shown in Fig. 4. The bar may also serve to operate a suitable alarm mechanism to indicate that the straight-ticket mechanism has been actuated.

70

I claim as my invention—

1. In a voting-machine, the combination with a casing, and a plurality of movable ballot-indicators therein, of a laterally-movable straight-ticket bar adapted to coöperate with the indicators and composed of independently-supported sections, means for coupling the sections for simultaneous operation and an actuating member attached permanently to one of the sections.

80

2. In a voting-machine, the combination with a casing, and a plurality of movable ballot-indicators therein, of a laterally-movable straight-ticket bar adapted to coöperate with the indicators to move them to voted position composed of independently-supported sections, means for coupling said sections for simultaneous operation and an operating means connected to one of said sections and independent of the coupling means for operating such of the sections as may be coupled.

85

3. In a voting-machine, the combination with a casing, and a plurality of movable ballot-indicators therein, of a laterally-movable bar for operating said indicators composed of independently-supported sections, each section adapted to coöperate with a definite number of indicators, said sections being provided with interlocking parts for coupling them directly and an actuating device for one of the sections.

90

4. The combination with a plurality of ballot-indicators, of an operating member therefor composed of a plurality of sections, each independently supported at one end only and detachably connected to the adjacent section at the other.

95

5. The combination with a plurality of ballot-indicators, of an operating member therefor composed of a plurality of sections, having detachable hooks at the ends for engaging adjacent sections and supporting-links for one end of each section.

100

6. The combination with a plurality of ballot-indicators of a longitudinally and laterally movable member for operating them, composed of detachable sections each section coöperating with different indicators.

105

7. The combination with a plurality of ballot-indicators of a movable operating member therefor composed of sections capable of separation when moved to an abnormal position and means for limiting the normal movement of said member.

110

8. The combination with a plurality of ballot-indicators, of a movable operating member therefor composed of a plurality of sections capable of separation when moved to an abnormal position means for limiting the normal movement of said member and means

115

120

125

130

for retaining disconnected sections out of co-operative relation with the others.

9. The combination with a plurality of ballot-indicators, of a movable operating member therefor composed of separate sections, an operating device connected to one section, detachable connections between said sections and means for holding the detached sections out of engagement with the section 10 having the operating device connected thereto.

10. The combination with a plurality of ballot-indicators, of an operating member therefor composed of a plurality of sections, 15 one section thereof being supported at both ends and the other sections supported at one end only and detachable connections between the adjacent ends of the sections.

11. The combination with a plurality of 20 ballot-indicators, of an operating member therefor composed of a plurality of sections one section thereof being supported at both ends, the other sections supported at one end only, detachable connections between the adjacent ends of the sections and means for holding the sections out of co-operative relation with the first-mentioned section.

12. The combination with a plurality of ballot-indicators, of an operating member 30 therefor composed of a plurality of detachable sections having engaging hooks at their adjacent ends, links supporting sections, and means for limiting the movement of the operating member in one direction.

13. The combination with a plurality of ballot-indicators, of an operating member 35 therefor composed of a plurality of detachable sections having engaging hooks at their adjacent ends movable means for limiting the movement of the member in one direction and means for holding the detachable sections out of co-operative relation with the others.

14. The combination with a plurality of 45 series of ballot-indicators of a plurality of the straight-ticket bars, one for each series, and each composed of detachable sections, means for operating said bars and means for holding the detached sections of the bars out of 50 co-operative relation with the others.

15. In a voting - machine an operating member consisting of a plurality of sections detachably connected at their adjacent ends

in combination with means for operating one of the sections and means for holding the other sections out of co-operative relation with the former. 55

16. The combination with the operating member composed of a plurality of sections, one section having two supporting-links connected thereto, and the other sections each having one supporting-link and cooperating projections and recesses, means for limiting the movement of the first section and retaining devices for holding the other sections out 60 of engagement therewith. 65

17. The combination with a plurality of series of indicators, a plurality of members each composed of a plurality of sections capable of disconnection when moved to an abnormal position and means for preventing the movement of all the members to said abnormal position. 70

18. In a voting-machine the combination with ballot-indicators, of a laterally and longitudinally movable operating member therefor and a vertically-movable bar with which said operating member co-operates. 75

19. In a voting-machine the combination with a plurality of series of ballot-indicators, 80 of a plurality of longitudinally and laterally movable operating members one for each series and a vertically-movable bar having projections thereon with which said members co-operate.

20. In a voting-machine the combination with a plurality of series of ballot-indicators, a plurality of laterally and longitudinally movable operating members one for each series having the beveled ends and the vertically-movable bar having projections with 90 which said beveled ends engage when the members are moved to one position.

21. The combination with a plurality of series of ballot-indicators, of a plurality of 95 operating members one for each series and each composed of sections detachable when moved to an abnormal position and a removable locking-bar adapted to engage the members and prevent the movement to detaching position. 100
